UNITED STATES PATENT OFFICE.

WILLIAM E. CLOW, OF CHICAGO, ILLINOIS.

DESIGN FOR A SINK.

SPECIFICATION forming part of Design No. 35,008, dated August 27, 1901.

Application filed June 22, 1901. Serial No. 65,698. Term of patent 14 years.

To all whom it may concern:

Be it known that I, WILLIAM E. CLOW, a citizen of the United States, residing at Chicago, in the county of Cook and State of Illinois, have invented and produced a new and original Design for Sinks, of which the following is a specification, reference being had to the accompanying drawings, which are made a part hereof, and in which—

10 Figure 1 is a perspective view of a sink embodying the new design. Figs. 2 and 3 are respectively a longitudinal and a transverse section thereof.

The principal novel features of the design 15 are the general oblong outline of the sink as a whole and the raised portion B, located centrally within the space bounded by the side and end walls, so as to leave between said raised portion and walls a continuous trough-like channel a, said raised portion and walls 20 being of substantially the same height.

The other features of the new design are the parallel front and back walls A, united

by curved end walls A', and a portion B, rising from the bottom A'' and located centrally 25 with respect to the said walls, so as to leave between it and the walls a continuous channel a, having parallel sides and curved ends.

Minor features of the design are the parallel side walls b b and curved end walls b' b', 30 surmounted by the plate b'' to form the raised portion B of approximately inverted-U shape in vertical cross-section.

Other minor features of the design are the external ribs or flanges C C, which extend 35 down the side walls A, thence beneath the bottom of the channel a, and thence up the side walls b of the portion B.

What I claim as new, and desire to secure by Letters Patent, is—

The design for a sink, substantially as herein shown and described.

WILLIAM E. CLOW.
